F. W. SEATON

LABEL FOR WOUND OR ROLLED FABRICS

Filed May 3, 1923

UNITED STATES PATENT OFFICE.

FREDERICK W. SEATON, OF LONSDALE, RHODE ISLAND, ASSIGNOR TO SAYLES FINISHING PLANTS, INC., OF SAYLESVILLE, RHODE ISLAND, A CORPORATION OF RHODE ISLAND.

LABEL FOR WOUND OR ROLLED FABRICS.

Application filed May 3, 1923. Serial No. 636,372.

To all whom it may concern:

Be it known that I, FREDERICK W. SEATON, a citizen of the United States, residing at Lonsdale, county of Providence, and 5 State of Rhode Island, have invented an Improvement in Labels for Wound or Rolled Fabrics, of which the following description, in connection with the accompanying drawings, is a specification, like 10 characters on the drawings representing like parts.

This invention relates to useful improvements in labels and more particularly to labels for cloth or other fabric wound or 15 supported upon a holder.

The holder, or "board" as it is frequently termed, may be of any character or form adapted to support the cloth or fabric but usually, as its name implies, it consists of a 20 flat board-like structure, either made of a single piece of material or built up from constituent parts, so that when the cloth or fabric is wound thereon, the ends of the holder or board appear at the end of the 25 cloth or fabric roll. For shipment, packing and other purposes, it is desirable that the holders or boards on which the cloth or fabric is wound occupy as little space as is consistent with the necessary dimensions 30 to secure strength and stability, and as a consequence, such holders are usually made only sufficiently thick to answer the above requirements, and the exposed ends of such holders offer little opportunity for the attachment of labels or other printed matter.

One of the objects of the present invention, therefore, is to provide a label which may be conveniently held between the surface of the holder or board and the cloth or fabric 40 wound thereon and present a label bearing portion having a label bearing surface extending uninterruptedly over one end of the holder or board and covering edges of the cloth or fabric wound thereon.

45 In accordance with the present invention the label comprises a leg portion and a label bearing portion, one of which is formed with a hinged leaf integral with and bent from the material of the leg or label bearing portion and secured to the other portion by an adhesive with an increased flexible line of fold extending longitudinally of the label bearing portion between its two longitudinal edges. The construction is such 50 that the labels may be folded into compact

form along the line of increased flexibility and nested or formed in compact packages. The line of increased flexibility or fold also adapts the label bearing portion to conform to irregularities in the relation of 60 the edges of the cloth wound upon the holder when the label is in place.

The various features and novel characteristics of the present invention will best be made clear from the following description and accompanying drawings of one good practical form thereof.

In the drawings:

Fig. 1 is a perspective view, with parts broken away, showing a holder or board 70 having cloth wound thereon and a label bearing placed in position;

Fig. 2 is an enlarged sectional perspective longitudinally on the line 2—2 of Fig. 1 of the holder and cloth, showing the hinge 75 leaf integral with the leg portion of the label with the exposed surface of the hinge leaf adhesively secured to the back of the label bearing portion with the line of increased flexibility nearer the upper edge of 80 the label bearing portion than the other;

Fig. 3 is a view similar to that of Fig. 2, but showing the hinge leaf formed integral with and bent from the leg and label bearing portions with the exposed surface of 85 the hinge leaf adhesively secured to the back of the label bearing portion;

Fig. 4 is a section through the holder and fabric wound thereon, showing the label in place;

Fig. 5 is a plan view of a blank from which the label may be conveniently formed; and

Fig. 6 is a perspective and sectional view longitudinally through the leg of the label 95 showing more particularly the line of fold of increased flexibility and the various positions that may be assumed by the label bearing portion with respect to the leg portion.

The holder or board 1 on which the cloth or fabric is wound or rolled may be of usual construction. In the present instance it is typified as a flat and substantially rectangular holder on which the cloth or fabric 2 is 105 wound layer upon layer. There is nothing peculiar in the holder or board or in the way of winding or rolling the fabric thereon.

In accordance with the present inven-

tion, the label is formed of card-board or other sheet material and is provided with a leg portion for insertion between a surface of the holder or board and the cloth or fabric wound thereon, and is connected to the label or information bearing portion by a more flexible line of fold extending longitudinally at the back of the information or label bearing portion between the 10 longitudinal edges thereof, the result being that the label itself may be folded into compact form for shipment or packing purposes, and the information or label bearing portion may adjust itself to unevenness in 15 the cloth wound upon the holder when the label is placed in position.

In the preferred form of the invention, as indicated in Figures 1 and 2, the label is formed of card-board and has a leg portion 3 of substantial wedge formation 4 to present an entering point 5 for the leg portion and the wide bearing surface between the board and the cloth wound thereon, to effectively hold the label frictionally in 25 place, but permitting ready insertion and removal of the label.

A part of the leg portion 3 beyond the exposed edge of the holder and fabric is bent transversely forming a transversely 30 extending line of fold 6 of increased flexibility and providing a leaf hinge 7, the exposed surface of which is adhesively secured to the back of the label bearing portion 8.

35 The leaf hinge 7 is preferably co-extensive with or only slightly shorter than the longitudinal dimensions of the label bearing portion 8 and is adhesively secured to the back of the label bearing portion 40 throughout its exposed surface by an adhesive 9 interposed between the exposed surface of the leaf hinge 7 and the back of the label bearing portion 8, thereby adding increased strength to the label bearing portion 45 along the adhesive connection between the two, yet permitting the label bearing portion 8 to be turned about the line of increased flexibility 6 between its upper and lower longitudinal edges.

50 Since the leg portion 3 of the label is to be inserted between one surface of the holder 1 and the cloth wound thereon, the leaf hinge 7 is adhesively secured to the back of the label bearing portion 8 to present 55 the fold line of increased flexibility 6 longitudinally of the label bearing portion at different distances from its longitudinal edges, so that when the label is placed in position, as indicated in Fig. 4, the inner 60 part of the label bearing portion, that above the leg 3, in the present instance, will cover the exposed edges of the cloth at one side of the holder, while the wider part of the label bearing portion, below the leg 3, will 65 cover the end of the holder and also the

edges of the cloth at the opposite side of the holder, and to add strength to the wider portion of the label bearing portion below the leg 3 the leaf hinge 7 is made of a width to extend from the more flexible line 70 of fold 6 to the lower longitudinal edge of the label bearing portion, as indicated in Figs. 1 and 2.

It may be desirable in some cases to form the entire label of a single piece, as indicated in Figs. 3 and 4, in which case the leaf hinge 7 may be formed integral with the leg portion 3 and the label portion 8, and bent along the line 10 extending longitudinally at one edge of the label bearing portion; in any event, however, the leg portion 3 and the label bearing portion 8 are connected by the more flexible line of fold 6 through the integrally formed leaf hinge 7 which has its exposed surface adhesively 85 secured to the back of the label bearing portion, as already described.

Where the leaf hinge portion 7 is formed integral with both the leg and the label bearing portion, the entire label may be cut 90 from a single blank, as indicated in Fig. 5, wherein the blank is formed with lines of weakness *a* and *b*, the former providing the more flexible line of fold connection between the leg portion 3 and the label bearing portion 8, while the line of fold *b* provides a guide for bending the material at 95 10 along the lower longitudinal edge of the label bearing portion.

From the construction described it will be 100 apparent that the leg portion 3 of the label and the information or label bearing portion 8 are connected together by the leaf hinge 7 along the line of increased flexibility 6 extending longitudinally between the upper and lower edges of the label bearing portion, with the result that the label bearing portion 8 may swing about the line of increased flexibility 6 into the varying positions indicated by Fig. 6, and the label 110 itself as a whole may be folded into compact form for packing and shipment, as indicated by full lines in Fig. 6, and when such labels are to be applied to the cloth wound or 115 rolled upon a holder the label bearing portion 8, previously folded as indicated by full lines, Fig. 6, may be readily swung into the dotted line positions and finally assume the condition indicated in Fig. 4, when the leg portion of the label is finally pushed 120 home.

A label for cloth wound upon a holder constructed in accordance with the present invention not only provides a structure 125 which may be readily applied to or removed from its connection with the cloth and holder, but by the flexible hinge connection between the leg portion and the label bearing portion, the latter may adjust itself to any unevenness in the edges of the cloth wound 130

upon the holder when the label is placed in position, and when labels are shipped or stored, the label bearing portion 8 may be folded flatwise relative to the leg portion 3 with the single ply of the label bearing portion 8 resting upon the surface of the leg portion, as indicated in Fig. 6, with the reinforced part of the label bearing portion which is adhesively secured to the leaf hinge 7 projecting slightly beyond the end of the leg portion, thereby materially decreasing liability of injury to the label bearing portion when the parts are in folded position.

What is claimed is:

- 15 1. A label for cloth wound upon a holder, comprising a card-board label bearing portion having an exposed face for the label, a card-board leg portion to be inserted between a surface of the holder and the cloth wound thereon and having the part which extends beyond the end of the holder and edges of the cloth bent to provide a hinge leaf integral with the leg portion and connected to the leg portion by a line of fold of increased flexibility, and an adhesive connecting the outer surface of the hinge leaf to the back of the label bearing portion.
- 20 2. A label for cloth wound upon a holder, comprising a card-board label bearing portion having an exposed face for the label, a card-board leg portion to be inserted be-

tween a surface of the holder and the cloth wound thereon and having the part which extends beyond the end of the holder and edges of the cloth bent along a transverse line of weakness to form a hinge leaf integral with the leg portion and connected to it by a line of fold of increased flexibility, the outer surface of the leaf hinge being adhesively secured to the back of the label bearing portion with the flexible line of fold nearer one longitudinal edge of the label bearing portion than the other.

3. A label for cloth wound upon a holder, comprising a card-board label bearing portion having an exposed face for the label, a card-board leg portion for insertion between a surface of the holder and the cloth wound thereon, a hinge leaf formed integral with one of said portions and bent along a line of fold of increased flexibility, and an adhesive between the surface of the hinge leaf and the other portion for securing the leg and label bearing portions together with the line of increased flexibility forming a hinge between the longitudinal edges of the label bearing portion and nearer one of said edges than the other.

In testimony whereof I have signed my name to this specification.

FREDERICK W. SEATON.
